UNITED STATES PATENT OFFICE.

WORDEN P. PENN, JACOB GEISS, AND JACOB BROSIUS, OF BELLEVILLE, ILL.

IMPROVEMENT IN HARVESTERS.

Specification forming part of Letters Patent No. **10,427**, dated October 27, 1863.

To all whom it may concern:

Be it known that we, WORDEN P. PENN, JACOB GEISS, and JACOB BROSIUS, of Belleville, in the county of St. Clair and State of Illinois, have invented certain new and useful Improvements in Harvesting-Machines; and we do hereby declare the following to be a full, clear, and exact description of the same, reference being had to the annexed drawings, making part of this specification, in which—

Figure 1 is a top view of our said improvement. Figs. 2, 3, and 5 are side elevations of three distinct improvements, which will be hereinafter explained; and Fig. 4 is an elevation of one of said improvements.

Our improvements consist, first, in a novel arrangement and combination of mechanical devices for raising and lowering the main frame of the machine. The drawings show two distinct plans of accomplishing this object, both of which we will describe; but in this application we will claim one of them only.

One of the plans aforesaid is shown by Fig. 2, which represents the inside of the main frame next to said figure, and consists of a segmental plate in the outside edge, whereof a worm-cog is cut, in which a worm-screw is made to gear. Said screw is fixed between two lugs, *u u*, cast on a bracket, *C*, bolted to the inside of the frame, as shown. The upper end of said screw is made square, so as to receive a wrench of corresponding form, by means of which it is operated and made to raise or lower the main frame on the segmental plate as a guide, said plate being fitted into a groove made in the bracket *e*, which groove or seat is formed by the hooks *H H*, cast on the bracket in the manner shown. The said segmental plate having the hub *D* made on its inside face, in which one end of the main shaft has its bearing, the frame will of course be raised or lowered, according as the screw is turned one way or the other. After the main frame has been adjusted said segmental plate is held in the desired position by means of one or more bolts, which pass through the bracket *e*, and are secured on the outside of the frame by screw-nuts, as shown.

Fig. 3 shows the inside of the outside frame-

piece of the main frame. In this figure the segmental plate *a* is secured to the frame by means of the bracket *e* and bolts in the same manner as in Fig. 2. The only difference between the two plans is in the manner of raising and lowering the frame, the plate in Fig. 3 being operated by a pinion, *f*, which gears in corresponding cogs cut in the convexed edge of the plate, a wrench being applied to the square end *r* of the pinion-shaft to operate it.

Our improvements consist, second, in a novel arrangement and combination of mechanical devices for the purpose of raising and lowering the platform *E* and out end of the finger-bar. The devices employed for this purpose consist of a bracket, *I*, bolted to the outside of the division-board and fastened to the finger-bar, as shown in Figs. 4 and 5, and in dotted line in Fig. 1. The lower part of said bracket forms the shoe for the sickle-bar to work through, and has ears made on the outside thereof, in which a screw, *O*, is arranged, as shown. Said screw passes through a socket, *N*, in which the arm *P* of the caster-wheel *R* is fixed, and when operated regulates the height of the finger-bar from the ground, the turning of the screw being accomplished by a wrench put on its upper end. The out end of the socket *N* is made broad, somewhat in the form of a fan-tail, with cavities *S S* cut in each side thereof to receive the end of the arms of the caster-wheel, by which means the position of the arms may be changed so as to raise or lower the finger-bar.

The screws used for raising and lowering the various parts herein referred to are held in position by means of stay blocks or pins passed through said screws, as may be most convenient.

Having now described the nature and construction of our improvements, what we claim as our invention, and desire to secure by Letters Patent, is—

1. In combination with the main frame, the segmental plate *a* and screw *b*, when arranged in respect to said frame, to each other, and to the main shaft, as shown and described, for the purpose specified.

2. The screw *O*, in combination with the

bracket I and division board or bar, and the socket N, for the purpose of raising and lowering the platform and out end of the finger-bar, as shown and described.

3. Making the socket N with a broad out end and with cavities therein, for the purpose of shifting the position of the arms P of the caster-wheel R, by which the out end of finger-

bar and platform can be raised or lowered, as shown and described.
